UNITED STATES PATENT OFFICE.

EDWARD WILLIAMS, OF CHARLEROI, PENNSYLVANIA, ASSIGNOR TO WILLIAMS WELDING & MANUFACTURING COMPANY, OF CHARLEROI, PENNSYLVANIA, A CORPORATION OF PENNSYLVANIA.

FURNACE DOOR.

REISSUED

Application filed July 29, 1927. Serial No. 209,274.

It is the object of this invention to provide a metal framed, refractory faced, water cooled furnace door, simple in structure, easily fabricated, adequate, and durable.

5 A door embodying my invention is illustrated in the accompanying drawings. Fig. I is a diagrammatic view, showing the door in front elevation, but with part of the refractory face broken away. Fig. II is a view 10 in vertical section, on the plane II-II, Fig. I.

The door of a furnace in which very high temperatures are maintained,—temperatures exceeding the melting point of iron,—the door of an open-hearth furnace, for instance, 15 must in that portion at least which is exposed to the atmosphere of the furnace chamber, be formed of highly refractory material. And, practically considered, the material must be fire brick or material of that class to 20 which the word "refractory" in more specific sense has come to be applied as its designation. Such material, being of relatively brittle and friable nature, lacking tensile strength and hardness, must, in order to constitute a movable and durable door, be carried in a frame, and the frame must, under practical limitations, be of metal. And the 25 frame of metal must, in order to endure the conditions of service, be made hollow and be 30 cooled by water or equivalent substance circulating within it.

The frame of my door I make of rolled steel pipe, and the frame consists of a peripheral portion 1, ordinarily of rectangular contour, and of intermediate transverse portions, in the form of one or more bars 2, extending across the space defined by the peripheral portion and at the ends opening into the pipe sections which constitute the peripheral portion. The transverse bars are less in thickness, transversely through the door, than is the peripheral portion of the frame, and they are arranged on the outer side, as will be seen on considering Fig. II, so 40 that the conductor walls on one side of the structure extend in common plane and on the other side form a re-entrant brick-receiving space. Such space may be filled solid with refractory material 3, and the inner face of 45 the finished door may within the peripheral portion 1 of the frame present a continuous face of refractory material.

The transverse bars 2 are spaced apart one

from another and from the lengths of pipe of which the peripheral portion 1 is formed, to 55 the end that the refractory body which faces the door on the inside may extend into and fill the spaces, and that thus a more securely integrated and more durable door may be 60 produced.

The refractory body 3 will ordinarily be built of bricks of standard size, 9 inches $\times$ 4 $\frac{1}{2}$ on the face. Accordingly I preferably form my door of rectangular rolled steel pipe of corresponding size, approximately 9 inches $\times$ 4 $\frac{1}{2}$. The rectangular periphery 1 of the door frame is formed of lengths of pipe set with the greater dimension (9 inches) extending in the direction of the thickness of the door. The lengths of pipe which form 70 the transverse bars 2 are set with the smaller dimension (4 $\frac{1}{2}$ inches) extending in the direction of the thickness of the door, and the greater in the direction of the lateral extent 75 of the door. The marginal portion extends transversely beyond the intermediate portion by a space interval equal, with tolerance, to the width of a standard brick. The spaces at which the transverse bars stand apart from 80 one another and from the lengths of pipe which constitute the sides of the door frame are, with proper tolerance, equal to the breadth of a brick (4 $\frac{1}{2}$ inches). The drawings show an integrated frame made up of 85 four peripheral lengths of pipe and three intermediate and transverse lengths. In the peripheral lengths openings are cut to receive the ends of the transverse lengths, and the components are welded along all lines of meeting.

The body of refractory material is built into the frame, and at proper intervals particular bricks 30 are laid extending lengthwise throughout the overall thickness of the door (9 inches) and into the spaces between 95 the pipes. Thus the refractory face of the door is bonded to the metal frame. All the spaces formed by transverse members 2 will 90 preferably be filled with masonry.

Circulation pipes are indicated at 4. The 100 use of such pipes is familiar. Any preferred arrangement of them may be adopted. With the matter of circulation in mind it will be remarked that the door preferably stands with the transverse members 2 in vertical 105 position.

The usual peep hole 5 may be formed through one of the members 2 and continued through the facing 3.

The door is provided with suspension lugs 5 6, as is usual.

I claim as my invention:

1. A supporting grid for brick-work which with the supported brick-work constitutes a furnace door, such grid being formed of 10 lengths of metallic conductor for liquid, fitted together, the structure including a marginal portion and an intermediate portion extending transversely between opposite members of the marginal portion, the marginal portion 15 extending transversely beyond the intermediate portion by a space interval equal, with tolerance, to the width of a standard brick, and the grid spaces being equal, with tolerance, to the width of a standard brick.
- 20 2. A supporting grid for brick-work which with the supported brick-work constitutes a furnace door, such grid being formed of lengths of metallic conductor for liquid of

cross-sectional dimensions corresponding to the length and width of a standard brick, 25 the structure including a marginal portion in which the conductor is arranged with its greater dimension transverse to the general extent of the structure, and an intermediate portion extending transversely between opposite members of the marginal portion, the conductor in such intermediate portion being arranged with its less dimension transverse to the general extent of the structure, the conductor walls on one 30 side of the structure extending in common plane and on the other side forming a reentrant brick-receiving space of a depth equal, with tolerance, to the width of a standard brick, and the grid spaces having a 35 width equal, with tolerance, to the width of a standard brick.

In testimony whereof I have hereunto set my hand.

EDWARD WILLIAMS.
